COOLING DEVICE FOR PRINTING MACHINES

Herbert G. Macdonald, Oak Park, Ill., assignor to
 Charles Bruning Company, Inc., New York,
 N. Y., a corporation of New York

Application October 17, 1940, Serial No. 361,545

6 Claims. (Cl. 95—77.5)

The present invention relates to printing mechanisms, and more particularly to an improved cooling device for use with rotary photo-printing mechanisms.

In printing mechanisms of the type commonly used in the art, a tracing and sensitized paper are passed continuously around a revolving cylinder which is formed of transparent material, generally Pyrex glass, and adapted to admit light to the paper from a centrally located light source. The cylinders so used are generally elongated in shape, i. e., of substantial length in relation to their cross-section, and the material from which they are formed, i. e., glass, is well known to be a poor conductor of heat. Accordingly, normal venting and cooling of the cylinder is negligible and, as a result, the heat produced by the centrally located light source rapidly raises the temperature of the glass cylinder to a point which is found to have undesirable effects upon the paper being printed.

Accordingly, it is an object of my invention to provide a device which is effective for controlling the temperature of the printing cylinder.

A further object of my invention is to provide a mechanism which is effective for controlling the temperature of the exterior surface of the printing roller.

Another object of my invention is to provide a venting mechanism which may be conveniently disposed within the printing cylinder so that a minimum amount of light is obstructed from the paper to be printed.

Another object of my invention is to provide a device for cooling the bands and the outer surface of the cylinder.

Other objects of my invention will be apparent from the following description of a preferred embodiment which is given in connection with the accompanying drawing, in which:

Figure 1 is a vertical sectional view of the venting mechanism as applied to a printing machine of the glass cylinder type; and

Figure 2 is a diagrammatic drawing of the venting mechanism and the printing cylinder.

Referring to the drawing, a glass cylinder 1 is supported on a plurality of endless bands 2 which are mounted on a feed roll 3 and a plurality of elongated rolls 4, 5, 6 and 7. At least one of the rolls is provided with driving mechanism (not shown in the drawing) for imparting movement to the bands and to the cylinder. The sensitized paper to be printed and the tracing are adapted to be inserted between the cylinder 1 and the endless bands 2 adjacent

the feed roll 3 and to be removed from between the cylinder and bands adjacent the roll 4. A light source 9 is disposed axially of the printing cylinder 1. The above described mechanism is well known to the art and commonly has been used in photoprinting operations.

In accordance with the present invention, means are provided for cooling the exterior and the interior of the cylinder 1 in order to prevent damage to the paper being printed.

The exterior of the cylinder 1 may be reduced in temperature by means of the bands 2. Preferably these bands 2 are made of dark-colored or black material so that they will absorb a greater proportion of the heat radiated upon them through the cylinder 1 than would the light-colored bands now commonly in use. Inasmuch as the dark-colored or black bands absorb and carry away a considerable amount of the total heat and do not reflect as much heat to be absorbed by the cylinder 1, the latter is maintained at an operating temperature insufficient to damage the printing paper. Cooling means supplemental to the bands may be provided, if desired, although in practice the dark-colored or black bands in conjunction with the venting and air-cooling means hereinafter described are sufficient to maintain the cylinder 1 at a satisfactory operating temperature.

The interior of the cylinder may be vented to reduce the internal temperature by means of an inlet duct 10 and an outlet duct 11 which are adapted to maintain a circulation of cooling air within the cylinder. The ducts 10 and 11 may be U-shaped in cross-section and preferably are sufficiently elongated to extend the entire length of the printing cylinder. Preferably the ducts 10 and 11 are disposed adjacent each other and adjacent the inner surface of the printing cylinder, between the feed roll 3 and roll 4. By being disposed in this manner, the ducts 10 and 11 do not intercept the passage of light from the source 9 to the paper to be printed. The inlet duct 10 is open at its ends to the atmosphere and is positioned so that the cooling air entering therethrough will be given a downward direction by the rotation of the printing cylinder. The outlet duct 11 is faced in the opposite direction to the inlet duct so that a circulation of air around the interior of the cylinder is effected.

One end of the outlet duct 11 is connected by means of an intake tube 12 to a blower 13 which is driven by any suitable power source, such as the motor 14. The blower 13 is provided with a

housing 15, which is connected to a baffle 16. The baffle 16 is disposed immediately below the endless bands 2 and the cylinder 1 and is adapted to disperse the air from the blower 13 across the entire length of the bands and cylinder and thereby to dissipate the heat from and cool the bands 2.

It will thus be seen that I have provided an effective mechanism for maintaining a positive flow of cooling air within the printing cylinder which reduces the temperatures in the interior of the cylinder. In addition, the air which is circulated through the cylinder is subsequently dispersed and directed against the endless bands to effect the cooling thereof. The bands in turn exert a cooling effect on the printing cylinder to provide an effective cooling action throughout. The circulation of air is sufficiently rapid to insure that the air withdrawn from within the cylinder by the blower is sufficiently low in temperature to cool the bands and cylinder.

It will be apparent that my invention is susceptible to many variations by one skilled in the art and all such variations are intended to be included within the scope of the following claims.

I claim:

1. A cooling device for a printing machine having a glass cylinder and a light source disposed within said cylinder normally causing the cylinder to become heated; said cooling device comprising a plurality of elongated members extending within and lengthwise of said cylinder and having a U-shaped cross-section for circulating cooling air within the cylinder, said members being disposed adjacent each other and adjacent the inner surface of the cylinder, said members being faced in opposite directions whereby the cooling air may be made to circulate from one to the other around the inner surface of the cylinder.

2. A cooling device for a printing machine having a glass cylinder, a plurality of endless bands partially encircling said cylinder, and a light source disposed within the cylinder and normally causing the cylinder and bands to become heated; said cooling device comprising a pair of elongated air conducting members extending within and lengthwise of said cylinder and in communication with the interior of the cylinder along the length thereof, one of said members being open to the atmosphere and pumping means communicating with the other of said members.

3. A cooling device for a printing machine having a glass cylinder, an endless band partially encircling said cylinder with a portion of its length while the remaining portion thereof is spaced from the cylinder, and a light source disposed within the cylinder and the band to become heated; said cooling device comprising a housing disposed adjacent the portion of the band spaced from said cylinder, and means to cause air to flow through the housing and against the band to dissipate heat therefrom.

4. A cooling device for a printing machine having a cylinder to support material to be printed, an endless band partially encircling said cylinder with a portion of its length while the remaining portion thereof is spaced from the cylinder, and a light source to direct light onto material supported on said cylinder and which normally causes the cylinder and the band to become heated; said cooling device comprising a housing disposed adjacent the portion of the band spaced from said cylinder, and means to cause air to flow through the housing and against the band to dissipate heat therefrom.

5. A cooling device for a printing machine having a glass cylinder and a light source disposed within said cylinder normally causing the cylinder to become heated; said cooling device comprising an elongated channel member extending within and lengthwise of said cylinder and directing cooling air substantially tangentially of said cylinder, and a second elongated channel member adjacent to said first mentioned channel member for withdrawing the air from said cylinder after it has traversed the major portion of the inner circumference of said cylinder.

6. A cooling device for a printing machine having a glass cylinder, a plurality of endless heat absorbing bands partially encircling said cylinder, and a light source disposed within the cylinder and bands to become heated; said cooling device comprising means for conducting air to the cylinder and directing it substantially circumferentially within said cylinder, means for withdrawing air from the cylinder after it has traversed the major portion of the circumference of said cylinder, and means for directing air against the bands to aid in cooling said cylinder.

HERBERT G. MACDONALD.
